UNITED STATES PATENT OFFICE.

HENRY A. WEIHMANN, OF PHILADELPHIA, PENNSYLVANIA.

DESIGN FOR A BRUSH-BACK.

SPECIFICATION forming part of Design No. 26,457, dated December 29, 1896.

Application filed October 16, 1896. Serial No. 609,154. Term of patent 7 years.

To all whom it may concern:

Be it known that I, HENRY A. WEIHMANN, of the city and county of Philadelphia and State of Pennsylvania, have invented a new and original Design for Backs of Brushes and Similar Articles, of which the following is a specification.

My design consists of the ornamentation applied to the back of brush-backs and similar articles, as shown in the accompanying drawings, in which—

Figure 1 shows the design applied to an approximately round brush or mirror back, and Fig. 2 is a modification showing the design applied to a back of oblate form.

The essential feature of the design consists of the wreath of roses A, with their stems and leaves arranged about the margin of the brush-back, with the central inclosed portion B plain.

The design is applied to the backs of brushes and hand-mirrors having handles, as shown in dotted lines, and also to those unprovided with such handles, such as military hair-brushes and clothes-brushes.

Having now described my invention, what I claim as new, and desire to secure by Letters Patent, is—

The design for the backs of brushes and similar articles substantially as shown and described.

In testimony of which invention I have hereunto set my hand.

HENRY A. WEIHMANN.

Witnesses:

ERNEST HOWARD HUNTER,
R. M. KELLY.
